UNITED STATES PATENT OFFICE.

FRANK C. RICHARDSON AND JOHN T. WOOD, OF IOLA, KANSAS.

OIL-BURNER.

1,023,529.

Specification of Letters Patent.

Patented Apr. 16, 1912.

Application filed November 21, 1911. Serial No. 661,563.

To all whom it may concern:

Be it known that we, FRANK C. RICHARDSON and JOHN T. WOOD, citizens of the United States, residing at Iola, in the county of Allen, State of Kansas, have invented a new and useful Oil-Burner, of which the following is a specification.

This invention relates to oil burners particularly designed for use in heaters, coal ranges, gas stoves, and the like so that oil may be used as fuel instead of coal or gas such as commonly employed.

One of the objects of the invention is to provide a durable and compact structure which can be easily placed on the grate of a heater or cook stove and which includes novel means whereby the vaporized oil will be thoroughly mixed with the air supplied to the burner in order that practically complete combustion may be obtained.

A further object is to provide improved means whereby the interior of the burner can be easily reached for the purpose of cleansing or repairing the same.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings the preferred forms of the invention have been shown.

In said drawings:—Figure 1 is a vertical transverse section through one form of burner embodying the present improvements. Fig. 2 is a plan view thereof. Fig. 3 is a plan view of the base of the burner, the burner rings being removed. Fig. 4 is a plan view of another form of burner particularly designed for use in coal ranges, a portion of the central baffle being removed. Fig. 5 is a perspective view of the baffle or mixing element. Fig. 6 is an end elevation thereof. Fig. 7 is a view partly in section of another form of burner, said burner being shown in perspective.

Referring to the figures by characters of reference 1 designates a hollow base supporting spaced circular troughs 2 and 3 which are concentric with an upstanding air nozzle 4 upon the middle portion of the

base. The base is preferably formed of two sections each of which is substantially semi-circular, said sections being provided with outstanding lugs 5 secured together by bolts 6 or the like while formed in the sections between the troughs 2 and 3 are webs 6 likewise bolted or otherwise secured together. It is to be understood that the troughs extend continuously so that oil is free to circulate therein and that an air space 7 is formed between the two troughs, the webs 6 intersecting this space. Additional reinforcing webs 8 may also be arranged in said space so as to reinforce the base structure. 70

An oil distributing pipe 9 is mounted in the base and under the meeting edges of the base sections, said pipe having nozzles 10 projecting into openings formed by registering notches 11 in the meeting edges of the base sections, two of these openings being provided within each trough at diametrically opposed points, as clearly shown in Fig. 3. A supply pipe 12 extends from the distributing pipe 9 and is adapted to receive oil from a casing 13 to which oil is fed from a pipe 14 or the like. A valve 15 is employed for controlling the flow of oil through the pipe 12. An air inlet pipe 16 opens into the base 1 and the pipe 12 is preferably extended longitudinally through this air pipe, there being an air inlet opening 17 located at any desired point in the pipe 16 so that air is free to enter the base 1. 80

Each of the troughs 2 and 3 is adapted to receive a burner ring 18 made up of opposed upwardly converging concentric plates forming a reduced outlet slot 19 which is concentric with the nozzle 4, there being openings 20 within each of these plates and close to the slot so that fuel is free to escape not only through the slot but also through the openings in the side plates of the ring. Each ring 18 is fitted snugly within the trough and has oppositely disposed annular offset portions or shoulders 21. 95

Concentric cylindrical casings 22 are supported by the shoulders 21 on the two rings 18, each of these casings being formed preferably of two semi-circular sections hingedly connected, as at 23 so that they can be opened out to give access to the interiors of the casings. These casings 22 cooperate to form two concentric mixing chambers 24 and 25 separated by an air chamber 26, the burner rings 18 being 100

adapted to discharge into the lower ends of the chambers 24 and 25 while the space 7 opens into the bottom of the chamber 26. All of the casings 22 are formed with 5 small apertures so that gases are free to circulate from one chamber to another. The central space surrounded by the inner casing 22 has a mixing element mounted therein, said element being made up of opposed 10 conical members 27 meeting at their apexes, there being a baffle disk 28 disposed around the meeting portions of the two conical members. Both of the conical members as well as the baffle disk are formed with small 15 apertures. The upper conical member has an apertured top plate 29 fitting snugly within the inner casing 22 while the lower conical member 27 is open at the bottom so as to receive air from the nozzle 4. Said 20 lower member preferably bears downwardly on a supporting ledge 30 formed on the base 1.

It will be apparent from the foregoing that when fuel is admitted to the base 1 and 25 ignited at the rings 19 the products of combustion will rise within the compartments 24 and 25 and commingle with air admitted to said compartments from the compartment 26 and the central space occupied by 30 the mixing element. The mixed air and unconsumed combustible particles will thus be ignited and as the temperature of the burner is raised the fuel will be completely vaporized within the troughs 2 and 3, the 35 vapor issuing from slots 19 and commingling with air supplied to compartments 24 and 25 whereupon the combustible mixture will be ignited and produce an extensive flame extending throughout the exterior surface 40 of the outer casing 22, the walls of the compartment 26, and the top of the mixing element 27. Obviously the casings 22 can be easily shifted off of the base 1 and opened outwardly upon their hinges 23 so that the 45 interiors of the casings can be easily cleaned and access be had conveniently to the interiors of the troughs 2 and 3.

It is to be understood that the burner may 50 be made of any other contours desired in order to fit properly within fire boxes of different shapes and sizes. In Fig. 4 a substantially oblong burner has been shown for use in the fire pot of a coal range. This burner is made up of a base 31 into which 55 the feed pipe 32 extends, there being a transversely disposed distributing pipe 33 arranged within the base and adapted to discharge fuel into the compartments between casings 34 upstanding from the base. 60 These casings coöperate to form spaced mixing chambers 35 which are substantially elliptical and which receive fuel from rings 36 mounted on the base 31. These rings have been shown in plan in Fig. 4 and 65 in cross sectional contour they conform

with the showing in Fig. 1. The space surrounded by the inner casing 34 is adapted to be occupied by a mixing element shown in detail in Figs. 5 and 6 and which is of the same cross sectional contour as the element shown in Fig. 1, but is elongated so as to extend throughout the length of the base. This element consists of upper and lower oppositely disposed members 37 the sides of which diverge from the center of the element, the upper member being closed by an apertured plate 38 constituting the top thereof while an elongated baffle plate 39 extends around the meeting portions of the upper and lower members. The operation 80 of this burner is the same as that described in connection with the burner disclosed in Figs. 1, 2 and 3.

Another form of burner has been illustrated in Fig. 7, this device consisting of an elongated trough-like base 40 having a fuel supply pipe 41 arranged therein. Apertured casing walls 42 extend upwardly from the walls of the base 1 and merge into an apertured top 43 from which extend downwardly inclined aprons 43'. Oppositely disposed plates 44 converge upwardly from the lower edges of the walls 42 so as to form a fuel outlet slot 45 extending longitudinally of the burner. Fuel discharged into the trough 40 from the pipe 41 is adapted to pass upwardly through the slot 45 and to mix with air admitted to the casing through the openings in the walls 42, said air entering the openings from the space formed under the aprons 43'. This type of burner is particularly designed for use in gas stoves in lieu of the ordinary gas burners.

What is claimed is:—

1. A hydro-carbon burner including a base having concentric troughs, an air space between the troughs, and a central air nozzle, said base being made up of detachably connected sections, means for directing air into the base, means for directing fuel into the troughs, upstanding casings having spaces therebetween communicating with the troughs, and burner rings mounted within the troughs and discharging into the spaces between the casings, each ring having a reduced fuel outlet slot extending continuously therein.

2. An oil burner including a base having concentric troughs thereon, there being an air space between the troughs and a central air nozzle, means for directing fuel into the troughs, means for directing air into the base, burner rings within the troughs and having reduced fuel outlet slots formed continuously therein, and casings upstanding from the troughs and adapted to receive fuel from the rings, each casing and trough and the base being made up of hingedly connected sections.

3. An oil burner including a base, cor

centric troughs thereon, there being an air space between the troughs and an air port surrounded by the troughs, means for directing fuel into the troughs, means for directing air into said space and port, burner rings removably mounted within the troughs, apertured casings supported by the rings and detachable therefrom, each of said casings consisting of movably connected sections, and an apertured mixing element removably mounted in the space surrounded by the inner casing, said element including upper and lower members having their sides diverging toward the outer ends of the members, said sides being apertured, and an apertured baffle plate surrounding the meeting portions of said members, said baffle plate and the upper and lower ends of the mixing element being extended throughout

the transverse area of the space within the inner casing.

4. An oil burner including a base, upwardly converging devices supported thereby to form a fuel outlet slot, means for directing fuel into the base and below the slot, apertured portions upstanding from the base, said slot being interposed between the apertured portions, and means for supplying air to each of said apertured portions.

In testimony that we claim the foregoing as our own, we have hereto affixed our signatures in the presence of two witnesses.
